UNITED STATES PATENT OFFICE.

CARL A. HAHN, OF ST. LOUIS, MISSOURI.

APPARATUS FOR AND METHOD OF ENAMELING WARE.

Application filed August 6, 1923. Serial No. 655,901.

To all whom it may concern:

Be it known that I, CARL A. HAHN, a citizen of the United States, and resident of the city of St. Louis and State of Missouri, have invented certain new and useful Improvements in Apparatus for and Methods of Enameling Ware, of which the following is a specification containing a full, clear, and exact description, reference being had to the accompanying drawings, forming a part thereof.

My invention relates to improvements in an apparatus for and method of enameling ware and has for its primary object an apparatus which can be readily heated and which will retain or store up a great amount of heat and in which any foul gases due to combustion can be readily driven away from the apparatus without materially lowering its temperature.

A further object is to construct an apparatus for enameling ware which is so arranged that none of the ware can fall into pockets and gradually clog the furnace necessitating a shut-down to remove such ware.

A still further object is to construct an apparatus which has the charging door so arranged that the weight of the door is used to hold the same firmly in closed position and thus prevent any escape of heat around the door.

A still further object is to construct an enameling furnace which is regenerative and in which a single valve controls the admission of air and fuel for heating purposes and the admission of air for scavenging.

In the drawings:—

Fig. 1 is a front elevation of my device with parts broken away;

Fig. 2 is a rear elevation of the same;

Fig. 3 is a vertical longitudinal section taken on the line 3—3 of Fig. 4;

Fig. 4 is a vertical cross section taken on the line 4—4 of Fig. 3;

Fig. 5 is a horizontal section taken on the line 5—5 of Fig. 4;

Fig. 6 is a front plan view of the valve housing with the cover removed showing the valve plate in position;

Fig. 7 is a horizontal section taken on the line 7—7 of Fig. 6 with the cover in position;

Fig. 8 is a front elevation of the valve housing showing the cam used for operating the oil valve;

Fig. 9 is an enlarged top plan view of the door with parts broken away and in section showing the same attached to a fragment of the furnace;

Fig. 10 is a fragmental vertical cross section of the door showing the same partly raised;

Fig. 11 is a vertical section taken on the line 11—11 of Fig. 10 showing the door slide resting on the stop and

Fig. 12 is an enlarged fragmental view illustrating the manner of securing the links to the door.

In constructing my apparatus I employ a front wall 13, a rear wall 14 and side walls 15. The walls forming preferably, a rectangle. Spaced apart from the side walls 15 are walls 16 which are connected together by means of an arch 17. The space between the walls 15 and 16 is filled with heat insulating material 18, such as asbestos fiber or any other commercial heating insulator. This insulating material is also placed over the arch, after which the space 19 may be filled in with clay or other material such as sand and the like. This securely holds the insulating material in place and also further prevents radiation of heat. The walls 16 and arch 17 form a chamber in the lower portion of which are arranged vertical walls 20 which divide that portion into a plurality of longitudinally extending passage ways 21. These passage ways in turn connect with passage ways 22 formed through the rear wall 14 and which open into the regenerating chamber 23. This chamber is provided with a flue 24 which connects with a chimney 25. The flue 24 is provided with a damper 26 by means of which the passage of gases through the chimney can be regulated. Through the rear wall is placed a combustion chamber block 27, to the rear of which is the oil burner 28. This oil burner has connected thereto an air pipe 29 and an oil pipe 30. The oil pipe is provided with a regulating valve 31 by means of which the amount of oil delivered to the burner is regulated.

Slidably mounted on the rear wall 14 is a

damper or closure 32 by means of which the opening through the combustion chamber block may be closed. The regenerator is provided with an arch 33 on which rests a coil of oil pipe 34, one end of this coil is connected to the oil pipe 30, and the other end to any suitable source of oil supply, not shown. The purpose of this coil is to furnish heated oil to the burner so that combustion can be more easily obtained. Within the regenerator 23 is a coil 35 one end of which is connected to the valve 36, the other end to the air pipe 29. This is for the purpose of supplying highly heated air to the oil burner where it mixes with the oil prior to entering the combustion chamber.

Resting on top of the walls 20 and on shoulders 36^a formed on the wall 16 are a plurality of blocks 37. These blocks forming the floor of the baking chamber 38. These blocks may be provided with openings 39 so as to permit the ready passage of heat from the passage ways 21 and into the baking chamber. It will be noted from Figs. 3 and 5 that the blocks 37 do not extend completely to the front wall but are spaced apart therefrom so as to form passage ways 40. The purpose of these will be explained in detail later.

Resting on the blocks 37 are ware setting tiles 41, these tiles are for the purpose of supporting the racks on which the ware to be enameled and baked is placed. The baking chamber 38 is provided with an opening 42 which is closed by means of a door constructed of a metallic shell 43. This metallic shell has vertical extending ribs 44 formed integral therewith, and the upper and lower edges of the casing 43 are provided with openings 45. Against the ribs 44 is placed a piece of sheet metal 46. This together with the openings 45 and ribs 44 forms air passages 47 which run vertical and prevent the door casing from becoming too intensely heated. Placed against the sheet 46 is a filling of heat insulating material 47^a. When this material is in place, the door facing 48 is placed in position. This door facing is constructed of refractory material as is all of the brick work used in the furnace. I may however, if it is desired to cheapen the construction, use ordinary building brick for the outside layer of the furnace walls. Pivotally secured to the casing 43 by means of studs 49 are links 50. These links have passing through their free ends rods 51, the ends of which have bearing in the door slides 52. These slides fit in channel shaped guides 53 which are placed on each side of the door and at some distance in front of the wall 13. The guides are secured to the furnace by means of straps or other suitable securing means 54. It will be noted from Fig. 11 that the slides 52 have openings 55 formed

therethrough, into which openings, the ends of the rods 51 are inserted and in order to prevent any shifting of the links, a tube 56 is placed between the links (see Fig. 9). Secured to the guides 53 is a slide stop 57, the purpose of which is to limit the downward movement of the door slides 52. The purpose of this limiting of the movement will be explained in detail later.

The top of the door is preferably provided with integral ears 58 to which are secured cables or links 59. These links come together and are secured to a ring 60 which is in turn secured to any suitable hoisting means 61. This hoisting means may be either an air hoist as illustrated, or may be a block and tackle, or any other suitable operating means. An air or electric hoist however, is preferable because the doors for a furnace of this type are extremely heavy, weighing in actual practice in excess of 1000 lbs. The entire furnace is preferably placed on a concrete foundation 62. On top of this foundation is placed a layer of insulating material 63, this is for the purpose of preventing the heat from reaching the concrete which might cause its cracking. On top of the arch 33 is a layer of insulating material 64 which is held in position by means of refractory tiles 65. Within the regenerating chamber 23 is a second air coil 66, one end of which is connected to the valve 36, the other end is connected to the rear wall of the furnace. This rear wall is provided with an opening 67 which is in alinement with the pipe and is for the purpose of permitting the air to enter the baking chamber 38 for scavenging the gases therefrom. The valve 36 consists of a housing 68, this housing is provided with screw threaded nipples 69, 70 and 71. Secured in the nipple 69 is one end of a pipe 72, the other end of which is connected to a blower 73. This blower is for the purpose of providing the necessary amount of air. Secured in the nipple 70 is the end 74 of the coil 35. The nipple 71 has secured thereto one end of the coil 66. The housing 68 is provided with a flange 75, to which flange the cover 76 is secured. Located within the housing is a disk 77, this disk is provided with a circular opening 78 which is designed to be brought in alinement with the screw threaded nipple 70 and with an arcuate opening 79 which is designed to be brought in alinement with the nipple 71. Extending through the cover 76 is a shaft 80 on which the disk 77 is mounted. The disk is held in close contact with the rear wall of the housing 68 by means of a coil spring 81. Secured to the shaft 80 and in front of the cover 76 is a cam 82 and a wheel 83. The wheel is for the purpose of turning the shaft 80 which simultaneously rotates the disk 77 and cam 82. Contacting with the cam 82 is a roller 84 which is

carried by the lower end of a slidably mounted rod 85. The upper end of the rod 85 is connected to a rocker arm 86 which is pivotally mounted in a bracket 87. The opposite 5 end of the rocker arm 86 is connected to a link 88, which link is in turn connected to a lever 89 carried by a valve 90. This valve is carried by the oil pipe 30 and is for the purpose of closing off the pipe when it is 10 desired to stop the firing. A spring 91 is connected to the rocker arm 86 for the purpose of holding the roller 84 in close contact with the cam and for closing the valve 90 after the cam has been so rotated that the 15 roller 84 passes its highest point. The oil is designed to be fed to the burner under pressure and as there are various devices on the market for this purpose, the same has not been shown nor has the burner been described in detail for the reason that it is one 20 of the many commercial types of burner now used.

The operation of my device is as follows:—

25 The oven door is first lowered into position so that the slides 52 contact with the stops 57. A continued lowering of the door now brings the links into action and permits the door to swing toward the furnace where its 30 weight holds it securely against the front of the furnace and closes the opening. The blower 73 is then started, after which the wheel 83 is rotated until the opening 78 is in alinement with the nipple 70. This permits the air to pass through the coil 35 and into the burner, at the same 35 time the cam is so rotated the valve 90 is opened, this permits the air and oil to reach the burner simultaneously and enter through the ignition chamber block, the slide 32 having been previously opened. It is of course, 40 essential that the damper 26 be also opened at this time. The heat generated by the burner passes into the baking chamber 38 and thence downward into the passage ways 45 21 through the openings 39 and 40. The heat then passes rearward through the 50 passages 22 and into the regenerator 23 and from there it passes up through the chimney. In this way in a short time the coils 35 and 55 66 become heated and deliver hot air which materially assists the combustion. After the proper temperature has been reached in the baking chamber, the lower portion of the 60 furnace is intensely hot also. The wheel 83 is then turned which removes the opening 78 from alinement with the nipple 70 and prevents any further passage of air through the coil 35. As soon as this closing off of air 65 has been accomplished the roller 84 leaves the highest point of the cam 82 and the spring 91 draws the rocker-arm 86 into the position shown in Fig. 2 simultaneously closing off the oil. The slide 32 is then lowered 70 to prevent ingress of cold air and egress of 65 heated air. A continued rotation of the hand-wheel brings the arcuate slot in alinement with the nipple 71, this permits air from the blower to enter the coil 66 become 75 heated and be delivered through the opening 77 into the interior of the furnace. This hot air completely fills the furnace and drives all of the foul gases in the furnace before it and out through the chimney and being highly heated does not materially 80 lower the temperature of the furnace, and by driving the foul gases out through the chimney there is no possibility of these gases escaping into the work room during the charging of the furnace and affecting 85 the health of the worker. After the furnace has been thus scavenged the hand-wheel is turned sufficiently far to bring the slot 79 out of alinement with the nipple 71, 90 both coils 35 and 66 are now cut off from the air supply and the damper 26 closed. This closes all openings to the furnace and prevents the admission of any additional air. The door is then raised so that the furnace 95 can be charged. In raising the door, the door will first move upward and away from the front of the furnace until it contacts with the uppermost rod (see Fig. 10). This prevents any further outward swinging of the door. A continued raising movement 100 now causes the slides 52 to move upward in the guides 53 thus clearing the opening 42 and permits the introduction of ware. After this the door is again lowered, as previously described, and when in this position 105 it will be impossible for the door to move outward and permit the escape of the heat from the baking chamber. Additional heat is constantly supplied from beneath the floor of the furnace through the openings 39 and 40 and as there is no outlet to the upper end of the baking chamber the heat is retained therein much longer than is possible 110 in furnaces where the baking chamber is connected to the chimney.

After the ware which has been introduced into the baking chamber has become heated to the desired degree necessary for baking the enamel thereon, which heating is accomplished by the radiation of the heat stored in the refractory masses of the sides, top and bottom and also in the passage ways 21 of the interior of the furnace, the ware is withdrawn and as this baking has lowered the temperature of the furnace slightly the firing operation and scavenging is repeated. The only difference being that after the furnace has been once heated, hot air is immediately supplied to the burner 28.

The regulation of fuel and the air supply to the burner by means of various valves and the duration of firing time permits a positive heat control inside the furnace. The heat

control being necessary for various kinds of ware to be enameled, the lighter ware, such as kitchen utensils and the like requiring a higher degree of heat than the heavier ware, 5 such as bathtubs and similar articles.

It is of course necessary in the construction of my device to provide suitable openings for the introduction of pyrometers so that the heat within the baking chamber can 10 be ascertained and regulated.

By the use of my device the scavenging of the furnace of foul gases is accomplished by a blast of highly heated fresh air. This 15 not only makes the operation quicker but a great deal surer than in the present type of 20 enameling furnaces where the only scavenging done is by the admission of air through the oven door. Furthermore after the scavenging is done and before the oven door is open, all communication with the chimney 25 is closed off thus preventing any ingress of cold air whereas in the previous type of furnace it was necessary in order to thoroughly 30 scavenge the oven, to leave the damper open momentarily, this naturally resulted in a loss 35 of temperature and it was necessary to heat the oven considerably more than was required for the baking temperature so that the temperature of the furnace would be 40 the proper degree after the scavenging was accomplished. This meant a longer firing period and resulted in the necessity of using more oil as well as using additional time for 45 the firing period. By the use of my device and method this firing period is materially 50 reduced and due to the consequent saving in time, the output of the furnace increased.

Another important feature of my device is the construction of the floor 37. In previous 40 devices it was possible for ware which fell off of the racks to fall down into the lower part of the furnace. This in time accumulated therein and necessitated the shutting down of the furnace for a considerable 45 time while this ware was being removed. The ware so dropped is of course rendered 50 useless and must be scrapped whereas in my device any ware falling off of the racks can be readily drawn out through the door by means of a suitable tool and as this is 55 done when removing the completed batch, this additional waste is eliminated.

By my construction a bottom or floor for the baking chamber is provided which has 55 great mechanical strength so that the heaviest articles can be baked therein and this bottom being supported by the solid partition walls furnishes an additional mass for 60 storing and disseminating heat directly underneath the ware which makes my device especially applicable for enameling extra heavy ware.

By the introduction of preheated air into the burner a great deal of the waste heat is 65 saved and the temperature of the flame is

increased because the gases issuing from the burner have already been highly heated before being ignited. This is a distinct advantage over the use of cold or only slightly warmed air being supplied to the burner. 70 Furthermore the preheating of the oil or fuel supplied to the burner also increases the efficiency of the flame due to the fact that it is not necessary to waste a great amount of heat units to bring the combustion mixture up to the igniting point and consequently a higher temperature can be reached in a shorter time, which results in an increased furnace output, the possibility 75 of quick changes from low to high temperature and the decrease of fuel consumption. 80

Another feature of my device is the location of the passage ways beneath the baking chamber, in so far as most of the heat is drawn downward near the door. This to a great extent eliminates the cooling of the forward portion of the furnace when charging because the major portion of the heat travels downward through the openings 40, 90 so that the forward portion of the oven attains a greater heat and when the damper is closed, this heat and heat from the passage ways 21 forms a cushion and prevents the entrance of cold outside air, which entrance of air has always been detrimental to heats in enameling furnaces wherein the scavenging was done through the door. 95

Furthermore in my device the heating of the refractory material has to be only slightly higher than the heat required for 100 vitreous enameling which is far below the destructive heating for high class refractory material. This assures an almost indefinite life for the refractory materials and the consequent absence of costly repairs and shutdowns. 105

While I have shown and described my device as utilizing an oil burner, I do not desire to limit myself thereto as either artificial or natural gases can be readily used for 110 heating with only slight modifications in the burner and air supply. Such modifications however, putting it within the province of anyone skilled in the burner art.

Having fully described my invention what 115 I claim is:—

1. The method of enameling ware which consists in bringing an enameling furnace to the desired temperature, scavenging the products of combustion from said furnace 120 through its chimney and without materially lowering the temperature of the furnace, and then inserting the ware to be enameled.

2. The method of enameling ware, which consists in bringing an enameling furnace to the desired temperature, scavenging the products of combustion from said furnace with preheated air, and then inserting the ware to be enameled. 125

3. The method of enameling ware which 130

- consists in bringing an enameling furnace to the desired temperature, scavenging the products of combustion from said furnace through its chimney with air under pressure and without materially lowering its temperature, and then inserting the ware to be enameled.
4. The method of enameling ware, which consists in bringing an enameling furnace to the desired temperature, scavenging the products of combustion from said furnace by preheated air under pressure, and then inserting the ware to be enameled.
5. The method of enameling ware, which consists in first bringing an enameling furnace to the desired temperature, scavenging the products of combustion from said furnace through the chimney while its charging and combustion chamber openings are closed without materially lowering its temperature, closing the chimney opening, and utilizing the heated air in the furnace to prevent the entrance of cold air while the ware to be enameled is being inserted.
6. The method of enameling ware, which consists in bringing an enameling furnace to the desired temperature, scavenging the products of combustion from said furnace with preheated air, and then inserting the ware to be enameled, closing all openings in the furnace and utilizing the heated air in the furnace to prevent the entrance of cold air while the ware to be enameled is being inserted.
7. The method of enameling ware which consists in bringing an enameling furnace to the desired temperature, closing the firing opening in said furnace, admitting air under pressure to said furnace for scavenging the products of combustion therefrom and without materially lowering its temperature, and driving said products of combustion out through the chimney, closing said air passage and chimney and utilizing the heated air in the furnace to prevent the entrance of cold air in the furnace while the ware to be enameled is inserted.
8. The method of enameling ware, which consists in bringing an enameling furnace to the desired temperature, scavenging the products of combustion from said furnace by preheated air under pressure, and then inserting the ware to be enameled, closing all openings in the furnace and utilizing the heated air in the furnace to prevent the entrance of cold air while the ware to be enameled is being inserted.
9. In an enameling furnace, a furnace having heating and scavenging means, a door adapted to move to and from said furnace and seat itself tightly against the front of the furnace by its own weight when in lowered position, and means for raising said door in and out of closed position.
10. An enameling apparatus comprising a front, a rear and two side walls, a baking chamber located within said side walls, a floor for said baking chamber, passage ways located beneath said floor and communicating with said baking chamber, a regenerating chamber in communication with said passage ways, air coils located in said regenerating chamber, a valve for controlling the admission of air to said coils, and means for projecting a heating medium into said baking chamber.
11. An enameling apparatus comprising a baking chamber having a charging opening and a floor, passage ways located beneath said floor, said passage ways having communication with the baking chamber adjacent the charging opening, means for projecting a heating medium into the baking chamber, means for scavenging the products of combustion from said apparatus, and a single valve for controlling the heating and scavenging means.
12. The enameling apparatus of claim 11 in which the floor of the baking chamber is reticulated.
13. An enameling apparatus comprising a baking chamber having a charging opening and a floor, passage ways located beneath said floor, said passage ways having communication with the baking chamber adjacent the charging opening, a closure for said charging opening, means for projecting a heating medium into the baking chamber, means for scavenging said baking chamber of the products of combustion, a regenerating chamber in communication with the passage ways, a plurality of air coils located within said regenerating chamber, said coils adapted to deliver heated air to the heating and scavenging means, and a single valve for controlling the admission of air to said coils in sequence.
14. In an enameling apparatus, a baking chamber having a floor, a regenerating chamber, and passage ways connecting said regenerating chamber and baking chamber, said passage ways located beneath the baking chamber, a fuel burner, means for supplying a preheated fuel to said burner, means for supplying preheated air to said burner, means for scavenging the baking chamber, air coils located within the regenerating chamber, said coils having communication with the fuel burner and scavenging means, and a single valve for admitting and closing off air to said coils, said valve adapted to close off the supply of fuel simultaneous with the closing off of air to the burner.
15. The method of enameling ware which consists in producing combustion in the baking chamber of an enameling furnace, scavenging the products of combustion therefrom without exposing the baking

chamber to atmospheric temperature, and lastly inserting the ware in said baking chamber.

16. The method of enameling ware which consists in producing combustion in the baking chamber of an enameling furnace, drawing the products of combustion downward beneath the floor of the baking chamber and permitting the same to pass out through a chimney, discontinuing said combustion by air under pressure forcing the products of combustion from the baking chamber and through the chimney, closing said chimney, opening the baking chamber and inserting the ware therein, and then closing the baking chamber.

17. The method of enameling ware which consists in producing combustion in the baking chamber of an enameling furnace, discontinuing said combustion, closing the combustion opening in the baking chamber, forcing the products of combustion from said baking chamber and out through the

chimney with preheated air, closing said chimney after the products of combustion have passed therethrough, opening said chamber and inserting the ware therein, and then closing said chamber while the ware is being baked.

18. In an enameling furnace, a furnace having a heating and scavenging means, a charging opening, a door adapted to be raised and lowered located before said opening, means for raising and lowering said door, and means carried by the door whereby the same is moved toward the furnace and seated tightly there-against by its own weight when the door is in lowered position, whereby said door is prevented from being forced away from the front of the charging opening by the expansion of air within the furnace.

In testimony whereof, I have signed my name to this specification.

CARL A. HAHN.
